FOOD VENDING STAND OR THE LIKE

Leo D. Guinan, 1118 Greenacre St.,
West Hollywood, Calif.

Filed Apr. 1, 1959, Ser. No. 55,299

Term of patent 14 years

(Cl. D13—1)

FIG. 1 is a front elevation of a food vending stand or the like embodying my new design,

FIG. 2 is a top plan view of the stand with the conventional, substantially rectangular building elements thereof broken away for convenience of illustration only, and

FIG. 3 is a side elevation thereof taken from the left as shown in FIG. 2.

The dominant feature of my design resides in the facade portion of the stand as best illustrated in FIGS. 1 and 2.

I claim:

The ornamental design for a food vending stand or the like, substantially as shown and described.
